UNITED STATES PATENT OFFICE.

AUGUST WEBER, SR., OF SCHENECTADY, NEW YORK, ASSIGNOR TO WEBER ELECTRIC COMPANY, OF SCHENECTADY, NEW YORK, A CORPORATION OF NEW YORK.

CASE FOR INCANDESCENT-ELECTRIC-LAMP SOCKETS.

1,145,105.

Specification of Letters Patent.

Patented July 6, 1915.

Original application filed August 4, 1906, Serial No. 329,153. Divided and this application filed December 19, 1914. Serial No. 878,189.

To all whom it may concern:

Be it known that I, AUGUST WEBER, Sr., a citizen of the United States, residing at Schenectady, county of Schenectady, and 5 State of New York, have invented certain new and useful Improvements in Cases for Incandescent-Electric-Lamp Sockets, of which the following is a specification.

The invention relates to such improvements and consists in the novel construction and combination of parts hereinafter described and subsequently claimed.

Reference may be had to the accompanying drawings, and the reference characters 15 marked thereon, which form a part of this specification. Similar characters refer to similar parts in the several figures therein.

Figure 1 of the drawings is a view in side elevation of an incandescent electric lamp-socket provided with my improved case. Fig. 2 is a similar view of the cap of the case detached. Fig. 3 is a horizontal cross-section of the cap, taken on the broken line 3—3 in Fig. 2. Fig. 4 is a view in side elevation, partly in vertical section, of the shell of the case in a position at right angles to that seen in Fig. 1. Fig. 5 is a horizontal cross-section of the case, taken on the broken line 5—5 in Fig. 1. Fig. 6 is a view in side elevation of a modified form of cap. Fig. 7 is a horizontal cross-section of the same, taken on the broken line 7—7 in Fig. 6. Fig. 8 is a view similar to Fig. 4, showing a modified form of construction of the shell.

35 This application is a division of an application filed by me August 4, 1906, Serial No. 329,153, for cases for incandescent electric lamp-sockets.

The principal object of my invention is to 40 provide for easily and securely connecting together, and for easily separating when desired, the cap and shell of a sheet-metal case, such for example, as the case of an incandescent electric lamp-socket.

45 Other objects of the invention will appear in connection with the following description.

Referring to the drawings wherein the invention is shown in preferred form, 1, 50 represents the shell or body and, 2, the cap, together comprising the case for an ordinary incandescent electric lamp-socket. The shell and cap are formed of sheet-brass or other sheet-metal and are adapted to be ap-

plied, one to the other, telescopically. For 55 use with a key-socket, the shell is provided with an open slot, 3, through which the shaft of the key, 4, projects.

In the keyless type of socket, said slot may be omitted, or it may be retained of 60 full or reduced dimensions to permit the compression of the shell, if desired to facilitate the separation of the interlocking parts of the shell and cap. The shell is provided near its larger end with one or more offsets, 65 5, which are tubular displaced portions of the sheet-metal itself of which the shell is made. The inner portions of the sides of these offsets are approximately at right angles to the body of the shell, and their outer 70 ends are beveled or tapered to facilitate the automatic interlocking of the parts as the case-members are telescopically assembled. The cap is provided, at a point or points 75 corresponding with the location of the offsets, 5, with an aperture or apertures, 6, cut therein adapted to receive said offset or the respective offsets.

In the preferred form of the invention the cap and shell are telescopically assembled by a movement having a rotational component; and as shown in Figs. 1, 2 and 3, the cap is provided, at one side of the aperture, 6, with a similar aperture, 7, the two apertures being connected by a slot, 8, 80 which tapers gradually from the aperture, 7, to the aperture, 6, whereat it is of less width than the diameter of said aperture and of the offset, 5, leaving the aperture, 6, enclosed by a wall formed by the cut edge of 85 the sheet-metal, extending considerably more than 180 degrees around the circumference of the aperture, whereby, when one of the offsets, 5, is seated in one of the apertures, 6, its removal from said aperture 95 along the slot, 8, is resisted by rigid cut edges of sheet-metal at the points, 9, in the path of perpendicular portions of the offset, 5. Leading from the aperture, 7, to the edge of the cap is a groove formed by 100 outwardly displacing the sheet-metal, as at 10.

In applying the cap to the shell, the groove, 10, is brought into line with an offset, 5, and the parts are assembled in bayonet fashion, by forcing the cap, first telescopically upon the shell, causing the offset, 5, to traverse the groove, 10, and enter the

aperture, 7, and then rotatively moving the cap upon the shell to cause the beveled end of the offset, 5, to travel along the slot, 8, until it enters the aperture 6. The offset, 5, being slightly beveled will center itself in the slot, 8, and be guided thereby, at the same time forcing outwardly the sheet-metal walls bordering said slot until the offset enters the aperture, 6, whereupon the resiliency of the sheet-metal walls of the slot, 8, cause them to resume their normal position, the final seating of the offset in the aperture, 6, being accomplished with a snap-action.

15 To separate the cap from the shell, the cap may be first rotatively moved in the opposite direction and then telescopically separated from the shell. The removal of the cap can be accomplished by compressing the shell by the fingers of one hand, while the cap is being removed by the other hand.

In the construction shown in Figs. 6 and 7, the aperture, 7, and slot, 8, are omitted, the cap being provided with a bayonet-shaped groove formed by displacing the sheet-metal, as shown at, 12, the outer end of said groove terminating at the edge of the shell, and its inner end at the aperture, 6, the inner end of said groove being of less 30 width than the diameter of the aperture, 6, and of the offset 5.

The operation of connecting and disconnecting the cap and shell in this construction is the same as above described. The edge of the shell is preferably provided with a notch, 13, at the mouth of the groove, which notch is adapted to receive the offset, 5, and serve as a guide in applying the cap to the shell. The cut-sheet-metal walls of the seat for the locking projection are rigid in that they do not yield to either rotative strain or pulling-apart strain, but offer positive resistance thereto, which prevents separation of the case-members until the inner 45 member is manually compressed. The sides of the offset or projection, 5, are substantially perpendicular so that they offer a positive resistance to said rigid cut-sheet-metal walls of the seat for the projection, 50 making it impossible to separate the case-members until the inner member is manually compressed; and in the preferred form of this projection its outer end is so beveled

as to enable the parts to automatically interlock with a snap action as the case-members are assembled, that is, no manual compression of the inner case-member is required in assembling and locking the case-members together. For convenience in pressing out the projection in tubular form 60 from the sheet-metal wall itself of the sleeve, an aperture, 15, may be formed in the outer end of the projection, as shown in Fig. 8.

What I claim as new and desire to secure by Letters Patent is—

1. An incandescent electric lamp-socket-case comprising a pair of sheet-metal members, one adapted to telescopically receive the other, the inner of said members being compressible, one of said members being provided with an aperture through its wall having rigid cut-sheet-metal edges, the other of said members having an integral tubular projection pressed out from its sheet-metal wall, said projection being 75 adapted to interlock with said aperture and having perpendicular sides presented to the rigid cut-sheet-metal edges of said aperture in a direction to prevent relative rotation and telescopic separation of the interlocked 80 members until the inner member is manually compressed.

2. An incandescent electric lamp-socket-case comprising a pair of sheet-metal members, one adapted to telescopically receive 85 the other, the inner of said members being compressible, one of said members being provided with an aperture through its wall having rigid cut-sheet-metal edges, the other of said members having an integral tubular 90 projection pressed out from its sheet-metal wall, said projection having a beveled end whereby it is adapted to automatically interlock with said aperture as the members are telescoped together and having perpendicular 95 sides engageable with the rigid cut-sheet-metal edges of said aperture in a direction to positively resist telescopic movement of separation and relative rotation of the interlocked members.

In testimony whereof, I have hereunto set my hand this 14th day of December, 1914.

AUGUST WEBER, Sr.
